UNITED STATES PATENT OFFICE.

HENRY J. BLAKESLEE, OF WEST HARTFORD, CONNECTICUT.

LIFE PRESERVER.

Application filed August 10, 1925. Serial No. 49,163.

To all whom it may concern:

Be it known that I, HENRY J. BLAKESLEE, a citizen of the United States, residing at West Hartford, in the county of Hartford 5 and State of Connecticut, have invented a new and useful Improvement in Life Preservers, of which the following is a specification.

This invention relates to the type of life preservers which are made of flexible material, for example elastic sheet rubber, and are adapted to be inflated with air to obtain the necessary buoyancy.

The object of the invention is to provide an article of this character which is simple and cheap to manufacture, whereby it may be sold at a low cost, which when deflated can be packed in a small space, so that it may be conveniently transported, which can 10 be easily inflated and sealed to give and retain the necessary buoyancy when about the neck of a user and hold the head above water whether the user is conscious or unconscious, and which is constructed without any metal 15 parts, such as fasteners, valves or seals which would be liable to rust or corrode and stick, rendering the device inoperative or ineffective.

In attaining this object the supporting body is formed as a tubular ring of flexible air-tight material having an interior 20 diameter that will fit rather closely about the neck of the user. A flexible inflating tube or nipple opening into the interior is 25 attached to the ring and a strip of elastic material is secured to the ring under and about which the nipple is folded and tucked when the ring is inflated for the purpose of 30 sealing the nipple and holding it so as to prevent the escape of air from the ring.

Fig. 1 of the accompanying drawings shows a plan of the article. Fig. 2 shows an edge view illustrating the manner in which the nipple is tucked under and folded about 35 the sealing strip.

The ring 1 is desirably made of thin elastic rubber, but may be made of other flexible air-tight and water-proof material. The nipple 2 is preferably made of a length 40 of flexible rubber tubing and it is attached to the edge of the ring over an opening into it, by a rubber patch 3. An elastic strip 4 has its ends secured to the ring adjacent to the patch. The ends only of this strip

are fastened to the ring, leaving a portion 55 between the ends not adhered to the ring but tightly drawn about the surface thereof. This strip has a short slit 5 through the portion that is not adhered to the ring.

The ring is inflated by blowing it up with 60 air through the nipple. This may be accomplished before the ring is placed over the head or after it has been located about the neck of the user. After the ring is sufficiently inflated to give the required buoyancy 65 the nipple is tucked under and folded about the slotted and loose section of the fastening strip, substantially as illustrated. The tension of the elastic strip compresses 70 the flexible nipple in such manner that the device is sealed so air cannot escape and permit the deflation of the ring. If the ring is inflated after it has been placed over the head of the user and it is made of elastic material, it expands in such manner that 75 it cannot be accidentally dislodged from the neck over the head, and thus it will support the head with the nose and mouth above water whether the user is conscious or unconscious. There are no metal parts in this device which can rust or corrode and thus 80 become inoperative or ineffective. It is easily inflated, and when deflated it may be folded into a very small space for transportation.

The invention claimed is:—

1. A life preserver comprising a tubular flexible air-tight water-proof ring adapted to be placed about the neck of the user, a flexible nipple opening into the ring and an elastic sealing strip attached to the ring and providing means whereby the nipple may be tucked under and folded about and be sealed thereby.

2. A life preserver comprising a tubular elastic rubber ring adapted to be placed about the neck of the user, a rubber nipple opening into the ring, and an elastic rubber sealing strip attached to the ring adjacent to the nipple, said strip having its ends but not its central portion adhered to the ring but with the central portion of the strip slotted and drawn tightly over the surface of the ring whereby the nipple may be tucked under and folded about the slotted central portion of said strip for compressing and closing the nipple.

HENRY J. BLAKESLEE,
